UNITED STATES PATENT OFFICE.

WILLIAM O. KAISER AND OSCAR KLEIN, OF BURLINGTON, IOWA.

POST-CARD RACK.

986,177.

Specification of Letters Patent.

Patented Mar. 7, 1911.

Application filed October 25, 1909. Serial No. 524,514.

To all whom it may concern:

Be it known that we, WILLIAM O. KAISER and OSCAR KLEIN, both of Burlington, Des Moines county, State of Iowa, have invented 5 certain new and useful Improvements in Post-Card Racks; and we hereby declare that the following is a full, clear, and exact description thereof, reference being had to the accompanying drawings, which form 10 part of this specification.

This invention is an improvement in racks for holding and displaying postal cards and the like for which we were granted Patent No. 934,318, September 14, 1909; and its 15 object is to improve the construction of the rack sections; to provide improved means whereby the sections can be supported; and improved means whereby the rows of sections can be simultaneously turned or rotated 20 so that the cards on opposite sides of the sections—which are double faced—can be displayed at, or readily viewed from, either side of the rack.

The invention will be clearly understood 25 from the following description and the accompanying drawings, in which—

Figure 1 is a side view of part of a rack embodying the invention. Fig. 2 is an enlarged horizontal sectional plan view on line 30 2—2, Fig. 1. Fig. 3 is an enlarged transverse section on line 3—3, Fig. 1. Fig. 4 is a section on line 4—4, Fig. 2. Fig. 5 is an enlarged detail sectional view on line 5—5, Fig. 3. Fig. 6 is an enlarged end view of 35 two connected rack sections. Fig. 7 is a plan view of a blank for the frame part and a rack section. Fig. 8 is an enlarged transverse section on the line 8—8, Fig. 6. Fig. 9 is an enlarged section on line 9—9, Fig. 8.

40 Each section or card holder of the rack is formed of sheet metal and comprises a bottom member 1, a top member 2, and end members 1^a. The end members 1^a and bottom member 1 are preferably stamped out 45 of a single sheet of metal (see Fig. 7) and the bottom member has its sides stiffened by return bend flanges, 1^c, the lower bends of which flanges are adapted to interlock with

the top member of another section, as hereinafter described.

50 The end members 1^a are preferably tapered as shown, being wider at top than at bottom, and are provided with inwardly projecting flanges 1^e on their outer edges as shown to retain cards in the rack; the end 55 members 1^a are also beveled on their upper ends as shown at 1^b so as to permit the more ready insertion and removal of cards from the section. The top member 2 is preferably 60 formed of sheet metal and is substantially rectangular in cross section and has a longitudinal slot 2^a in its upper side.

The upper ends of the side members 1^a of the frame are attached to the ends of the tubular top member 2 in any suitable manner; a good and preferred form of connection is to form ears or flanges 1^m on the upper ends of the side members 1^a, which ears embrace opposite sides of the ends of the top member 2 and are fastened thereto 70 by riveting, or preferably eyeletting, the ears 1^m to the sides of member 2 as indicated at 1ⁿ, and clearly shown in Figs. 8 and 9. The end members may be stiffened by corrugating them as indicated at 1° and 1^p, 75 the central corrugation 1° being the deepest and serving as a means to prevent short cards inserted in one side of the section tipping over to the other side thereof.

80 The flanges 1^e on one section can be engaged with the slotted top member 2 of another section, as indicated in Figs. 1—3; and any number of such sections can be connected together in a vertical row. We have shown but two sections so connected 85 in the drawings, but obviously more sections can be used if desired.

85 The uppermost section of each row is suspended by a hanger 3 attached to a rotatable stub shaft 5^a journaled in the support 90 5. This hanger 3 is preferably made of sheet metal, and is bent to form a head portion 3^b, a shank 3^c and clips 3^d. The head portion 3^b of the hanger is inserted in the top member 2 of the upper section with the 95 shank 3^c projecting above the same through

slot 2^a; and the clips 3^a of the hanger 3 are suitably fastened to the lower ends of the stub shaft or pin 5^a, as by a bolt 3^a. The stub shafts 5^a are journaled in openings in the 5 upper side of the support 5, and in cross pieces 5^b attached to the support.

As shown the support 5 is formed of an inverted U-shaped metal bar, or plate, and the cross pieces 5^b are preferably formed of 10 metal straps riveted or otherwise secured to and between the depending side flanges of the support 5 at the proper points. The stub shafts 5^a are supported on the cross pieces 5^b preferably by means of pinions or 15 gears 4 which lie upon cross pieces 5^b and have angular axial openings through which the stub shafts 5^a depend; the lower parts of said shafts are angular in cross section, like the openings in the pinions 4, so as to cause 20 the shafts to turn with the pinions. The teeth of the pinions project slightly beyond one side of the support 5 through slots 5^c in one side flange of the support, as shown.

On the slotted side of support 5 is a slide-bar 6 which is provided with series of teeth or slots 6^a adapted to be engaged by the pinions 4, so that if the slide-bar be shifted longitudinally all the pinions will be rotated similarly—and consequently the rack sections connected therewith can be turned. 25 The slide-bar 6 may be upheld in position by lips 6^b struck up out of the metal of the support as indicated in the drawings. Said slide 6 may be operated by means of a hand-rod 8 attached to the lower end of one of 30 the stub shafts 5^a as shown in Figs. 1 and 2, so that by turning rod 8 by hand the slide-bar 6 can be shifted to right or left, and will cause the several pinions to rotate alike; and 35 thus the rows of sections can be simultaneously turned to right or left at will. The pinions 4 are provided with projecting stop portions 4^c adapted to strike the side of the slotted flange of support 5 and to arrest the 40 rotation of the pinions when they have made a one-half revolution in either direction which will suffice to completely reverse the rack sections, and to stop them when they 45 are exactly parallel with the support.

50 In practice any desired number of the card holding rack sections may be connected in a row, and any desired number of rows of such sections can be suspended from the support 5; and in this way a display rack 55 of any desired size can be readily built up, with cards displayed on both sides of each section. In order to reverse the racks it is simply necessary to turn the rod 8 sufficiently to impart a semi-rotation to the pinions 4 60 which will turn each row of rack sections half-way around, and thus reverse the positions of such sections, so that all the cards

on both sides of the rack can easily be shown to a customer.

Having described our invention what we 65 claim as new and desire to secure by Letters Patent thereon is:

1. In a display rack, the combination of a support having depending side flanges, cross pieces secured between said flanges, pinions supported on said cross pieces, and stub shafts transfixing said pinions, a slide bar 70 engaging all of the pinions, display racks suspended from said shafts, and an operating rod connected with one of the shafts. 75

2. In a display rack the combination of a support, a pinion mounted on said support, a display rack suspended from said pinion, and manually operable means for turning the pinion, said pinion having stops on its 80 periphery whereby it is arrested when turned a half revolution in either direction.

3. In a display rack, the combination of a metallic supporting bar having depending side flanges, a cross piece secured between 85 said flanges, a pinion supported on said cross piece, a stub shaft journaled in the bar and cross piece and connected to the pinion and supported thereby, a display rack suspended from said stub shaft, and a sliding rack bar for turning said pinion. 90

4. In a display rack the combination of a support, a stub shaft mounted on the support, a display rack suspended from said shaft, a segmental pinion on said stub shaft 95 having stop portions whereby the rotation of the pinion is arrested when turned a half revolution in either direction, and manually operable means for turning said shaft.

5. In a card exhibiting section for display racks the combination of a single integral U-shaped frame having integral bottom and side members, the bottom member of the said frame having oppositely disposed integral side flanges and the end members being tapered from bottom to top, and having 100 inwardly extending flanges on their outer edges; with a top member connected to and between the upper ends of the said side members, and having a longitudinal slot 105 adapted to be engaged by the flanges of the bottom member of a similar section. 110

6. A card-display rack section comprising a U-shaped frame having a bottom member provided with flanges on its edges, and integral end members tapered from bottom to top, having inwardly extending flanges on their outer edges and inwardly projecting ears on their upper ends provided with struck-up parts; with a slotted tubular top member having openings in its sides engaging said struck-up parts of the ears on the end members, substantially as described. 115 120

7. A display section for card racks com-

prising a tubular top member having a longitudinal slot in its upper side; with a frame having a bottom member provided with return-bend flanges on its sides, and 5 end members formed integral with the said bottom member but wider at top than at bottom and having inwardly projecting side flanges, and having ears on their upper ends embracing the ends of the top member and 10 secured thereto; the flanged bottom member

of one section being adapted to engage the slotted top member of a like section.

In testimony that we claim the foregoing as our own, we affix our signatures in presence of two witnesses.
